UNITED STATES PATENT OFFICE

CARL G. KRONMILLER, OF CHICAGO, ILLINOIS, ASSIGNOR TO BATES VALVE BAG COMPANY, OF CHICAGO, ILLINOIS, A CORPORATION OF WEST VIRGINIA.

TAPE CUTTER.

Application filed May 3, 1926. Serial No. 106,381.

This invention relates to a cutter, and particularly to a cutter adapted to cut a tape between bags or a similar series of articles to which the tape has been attached. The 5 construction and details of the invention will appear as the description proceeds.

In the accompanying drawings, forming a part of this specification, Figure 1 is a somewhat diagrammatic plan view illustrating the relation of the cutter to the tape and bags during the cutting operation; Fig. 2 is an enlarged plan view of the cutter proper; Fig. 3 is an end view of the cutter; Fig. 4 is a front view of the cutter; Fig. 5 is a section of the cutter on the line 5—5 of Fig. 3; Fig. 6 is a detail of the drive mechanism on the line 6—6 of Fig. 5; Fig. 7 is a detail of the cutter blades on the line 7—7 of Fig. 5.

In Fig. 1 there are shown bags 10 to which 20 a tape 11 is sewed by means of a needle 12. The bags are shown spaced apart at 13. The cutter is intended to cut the tape at each space 13 as a series of bags with tape attached thereto is fed through the mechanism.

A bracket 14 attached to any suitable portion of the frame of the apparatus carries a bearing for a stem 15 of a U-shaped frame 16. A drive shaft 17 is mounted in the 30 frame 16 and may be driven by a pulley 18, or any suitable means. Drive shaft 17 carries an eccentric 19.

A cutter shaft 20 is mounted in the front end of the U-frame parallel with shaft 17. 35 Shaft 20 carries a ratchet wheel 21, rotation of the shaft with the wheel being insured by a key 22. The ratchet is adapted to be engaged by a pawl 23 pivoted to a lug 24 on a sleeve 25, which is oscillatable about shaft 20. A drive arm 26 on sleeve 25 is connected by link 27 to eccentric 19, and by this means the sleeve and pawl are oscillated about the axis of shaft 20.

A stationary cutter disc 28 is mounted 45 loosely on the end of shaft 20 between the arms of U-frame 16. There are holes 29 in cutter disc 28 adapted to receive pins 30 which are fixed in position in one of the arms of frame 16.

50 A star cutter wheel 31 is mounted on shaft 20 in position to cooperate with cutter disc 28. Cutter 31 has holes 32 adapted to slip over pins 33 mounted in a flange 34 on shaft 20.

Shaft 20 is mounted in a bearing 35 in one 55 arm of the U-shaped frame, that at the left as viewed in Fig. 5, while a bearing 36 in the other arm of the frame supports the other end of the shaft. A sleeve 37 surrounds shaft 20 in bearing 36, and extends 60 through sleeve 25. Sleeve 25 is fastened to sleeve 37 by means of a set screw 38. If sleeve 37 is pressed tightly into bearing 36, or otherwise secured therein, screw 38 may 65 be omitted.

A bracket 39 is fastened by screws 40 to the underside of the U-frame and has a forked end 41 which embraces shaft 20 and holds ratchet wheel 21 in place against the end of sleeves 25 and 37. Elongated key-way 42 in 70 shaft 20 allows the shaft to move longitudinally with respect to ratchet wheel 21 and key 22.

A cap 43 is screwed upon the outer end of sleeve 37. Cap 43 has a central opening 44 75 therethrough, which opening is countersunk at 45. A pin 46 passes through this hole, the head 47 of the pin working in the countersink. On the other end of the pin there is a hardened wear block 48 adapted to contact 80 a ball 48' in the end of the shaft 20. A spring 49 normally presses wear block 48 against the end of shaft 20 and thus holds flange 34 against the star cutter 31, which, in turn, presses against stationary cutter 28. 85

From the upper side of frame 16, adjacent the cutter wheels, there arises a bracket 50 provided with a bearing 51 for a shaft 52. Shaft 52 is provided with a block 53, which is adjustably fastened to the shaft. A crank-shaped trip-carrying rod 54 is adjustably 90 fixed in block 53. Rod 54 carries a trip plate 55 bevelled on its underside, as at 56, where it meets the oncoming bags, and having a notch 57 in its rear edge. 95

Block 58, similar to block 53, is adjustably fixed on shaft 52 and carries a rod 59 from the end of which there projects a leaf spring 60. Beneath the spring 60 there is a downwardly curved pusher 61. 100 The end of spring 60 is connected to pawl 23 by means of a link 62. Gravity alone may be depended upon to engage pawl 23 with ratchet wheel 21, but preferably a torsion spring 63 is employed for this purpose. 105

The operation of the device is substantially as follows. It will be readily understood that, when drive shaft 17 is rotated, sleeve

25 is oscillated by means of eccentric 19 and link 27. This oscillates pawl 23 about the axis of shaft 20. When the pawl moves to the left, as viewed in Fig. 6, it engages teeth 6 on ratchet wheel 21 and thereby forces the shaft and star wheel cutter to move. The parts are so proportioned that each revolution of the shaft 17 causes the star wheel cutter to move the distance of one tooth or 10 arm. In the structure shown, the star wheel cutter has eight arms, and, therefore, the parts are proportioned to give the cutter one-eighth of a turn at each revolution of shaft 17. It will be readily seen that this one-eighth revolution will cause the arm of the star wheel cutter to move downward past the knife edge 64 of cutting disc 28 and shear off any tape lying in notch 65 of disc 28.

Trip plate 55 is so mounted and adjusted 20 that, when it rides on a bag 10, it oscillates shaft 52 and elevates pusher 61 so as to raise the outer end of spring 60, and, through link 62, raises pawl 23 out of engagement with ratchet wheel 21.

25 When the trip plate drops into a space 13 between adjacent bags 10, shaft 52 is oscillated so as to no longer raise pawl 23, and, upon the next reciprocation of the pawl, the star wheel cutter is moved through one-eighth of a revolution and cuts the tape and the seam in notch 65. If the bags are fairly close together, the trip plate rides up on the next bag and raises spring 60 before the cutting is completed. However, the parts are 30 so proportioned that spring 60 does not apply sufficient force to lift pawl 23 out of engagement with ratchet wheel 21 as long as the pawl is shoving against the tooth of the ratchet wheel; but, when the pawl starts back and is disengaged from the tooth of the ratchet wheel, spring 60 raises it sufficiently so that it will not again engage the ratchet wheel until the trip plate once more drops. It will be readily understood that, if there 35 is considerable space between successive bags, the trip plate may not be raised during two or more strokes of the pawl, and the cutter will be rotated and continue to cut off successive lengths of the tape until the next bag 40 is reached. In this way the cutter automatically cuts off the tape as soon as a bag has passed from under the trip, and continues to cut the tape until the trip is raised by another bag. Therefore, the tape will be cut 45 off adjacent the edges of each bag regardless of the length of the space between successive bags.

When the cutter plates become dull, they 50 are removed in the following manner. Cap 43 is unscrewed sufficiently so that shaft 20 may be shoved to the right, as viewed in Fig. 5, enough to withdraw the end of the shaft from cutter 28, and thereupon cutter 28 may be pulled off of pins 30 and removed from 55 the apparatus, for resharpening. Another

cutter plate 28 may be slipped into position, if it is desired to use the machine without waiting to sharpen the dull cutter. Similarly, cutter 31 may be pulled off of pins 33 and slipped off of the end of shaft 20, when the shaft is in its farthest position to the right. In this way it will be seen that the cutters are held firmly in position and pressed against each other during the operation of the device, and at the same time may be 70 very readily and quickly removed and replaced when desired. The operation of the cutter is positive and accurate, and provision is made for stopping the cutter when desired without allowing it to stop at any time 80 with an arm of cutter 31 opposite notch 65 in knife 28, because, whenever pawl 23 is engaged with ratchet wheel 21, it remains in engagement therewith until its stroke is completed, whereby the respective cutting arm of cutter 31 is moved below notch 65.

It will be understood that various changes may be made in the construction and operation of the described device within the terms of the appended claims which define the invention.

What I claim is:

1. In apparatus of the character described, a stationary cutter, a movable cutter adapted to cooperate with the stationary cutter, a shaft carrying the movable cutter, means for rotating the shaft, and means normally pressing the shaft and movable cutter towards the stationary cutter.

2. In apparatus of the character described, a bearing, a stationary cutter attached to one side of the bearing, a shaft extending through the cutter into the bearing, a movable cutter mounted on the shaft for rotation therewith, means to rotate the shaft, and means normally pressing the shaft and movable cutter towards the bearing.

3. In apparatus of the character described, a bearing, pins projecting from one side of the bearing, a stationary cutter removably mounted upon the pins, a shaft extending through the cutter and into the bearing, a cutter mounted on the shaft for rotation therewith adjacent the stationary cutter, and means normally pressing the shaft 110 and cutter mounted thereon towards the bearing.

4. In apparatus of the character described, a bearing, pins projecting from one side of the bearing, a cutter removably mounted upon the pins, a shaft extending through the cutter and into the bearing, a flange on the shaft adjacent the bearing, pins extending from the flange towards the bearing, a cutter mounted upon the last said 120 pins and slidably axially of the shaft, and means normally pressing the shaft towards the bearing.

5. In apparatus of the character described, a stationary cutter, a bearing, a 130

- shaft slideable in the bearing towards and from the cutter, a rotary cutter mounted on the end of the shaft towards the stationary cutter, a drive wheel splined on the shaft, means for retaining the drive wheel in fixed axial position, and a spring normally pressing the shaft and cutter carried thereby towards the stationary cutter.
6. In apparatus of the character described, a stationary cutter, a star wheel cutter having a plurality of arms each adapted to cooperate with the stationary cutter, a shaft, means connecting the star wheel cutter to the shaft for rotation therewith, a ratchet wheel splined on the shaft, means for intermittently moving the ratchet wheel and a spring normally tending to press the shaft and star wheel cutter towards the stationary cutter.
7. In apparatus of the character described, a bearing, a shaft slidably mounted in said bearing, projections from one side of the bearing substantially parallel with the shaft, a stationary cutter mounted on the projections, a flange on the shaft adjacent the cutter, projections on the flange extending towards the cutter, a rotary cutter mounted upon the last said projections, a second bearing, and means connected with the second bearing, for pressing the shaft axially in a direction to hold the cutters against each other.
8. In apparatus of the character described, two spaced bearings, a stationary cutter removably attached to the inner side of one of said bearings, a shaft slideable through said bearings, a drive wheel splined on the shaft and secured against axial movement on the inner side of the other bearing, a rotary cutter removably attached to the shaft in position to cooperate with the stationary cutter, a spring on the outside of the second said bearing, and adjustable means to hold the spring compressed against the end of the shaft.
9. In apparatus of the character described, a cutter, means to feed past the cutter spaced articles connected by a tape, driving means normally intermittently engaged at regularly recurring intervals for driving the cutter, a trip normally in the path of an article approaching the cutter, and means actuated by the trip, when moved from the path of the article, to prevent the re-engagement of the driving means until the next period of normal engagement of the driving means after the trip returns to its normal position.
10. In apparatus of the character described, a stationary cutter having a notch therein, a rotary cutter having arms thereon movable successively past said notch, intermittently engaged actuating means adapted to rotate the cutter at each engagement a sufficient distance to move one of its arms past said notch, means to feed past the cutter a series of spaced articles connected by a tape with the tape passing through said notch, a trip in the path of the articles, and means connecting the trip to the cutter actuating means and adapted to allow the completion of a cut started before the trip is actuated and to prevent re-engagement of the actuating means while the trip is in contact with the article.
11. In apparatus of the character described, a cutter, means to feed past the cutter spaced articles connected by a tape, driving means normally intermittently engaged at regularly recurring intervals for driving the cutter, a trip normally in the path of an article approaching the cutter, and means actuated by the trip, when moved from the path of the article, to prevent the re-engagement of the driving means until the next period of its normal engagement after the trip returns to its normal position, the said means actuated by the trip including a spring yieldable sufficiently to allow movement of the trip out of the path of the article by the article, and means to utilize the energy thus stored in the spring to prevent re-engagement of the driving means.
12. In apparatus of the character described, a cutter, means to feed past the cutter spaced bags connected by a continuous closure-forming member, intermittently engaged actuating means for the cutter, a trip normally extending through a space between bags and having a cam surface in the path of an oncoming bag and adapted to move the trip a distance greater than the thickness of the bag walls, and yielding means connected to the trip and operative when the trip is moved by a bag for maintaining the actuating means disengaged after it has been disengaged in its normal intermittent operation, the yielding means being adapted to yield sufficiently to allow the trip to move from in front of a bag without disengaging said actuating means while actuating force is being applied to the cutter.
13. In apparatus of the character described, a stationary cutter having a notch therein, a rotary star wheel cutter, a shaft upon which the star wheel cutter is mounted, a ratchet wheel mounted upon the shaft, a pawl mounted for oscillation in cooperative relation with the ratchet wheel, means for oscillating the pawl a distance sufficient to move one arm of the star wheel past the notch, means to feed a series of spaced articles connected by a tape past the cutter with the tape passing through the notch, a trip adjacent the cutter in the path of the articles, and yielding means connecting the trip and the pawl, the parts being so proportioned that said yielding means will not operate to pull the pawl out of contact with the ratchet while the cutter is being actu-

ated, but will prevent the reengagement of the pawl with the ratchet while the trip is in contact with an article.

14. In apparatus of the character described, a bearing, pins projecting from the one side of the bearing, a stationary cutter mounted on the pins and having a notch therein, a shaft having one end mounted in the bearing, a flange on the shaft having 5 pins projecting towards the cutter, a star wheel cutter mounted on the last said pins, a second bearing for the other end of the shaft, a ratchet wheel splined on the shaft and fixed axially with respect to the second 10 pins, a spring, and means adjustably connected with the second said bearing for compressing the spring against the end of the shaft, a pawl oscillatable about the shaft 15

in position to engage the ratchet, means for oscillating the pawl a distance sufficient to 20 move one arm of the star wheel past the notch, a spring normally tending to cause the pawl to engage the ratchet, means for conveying past the cutters a series of spaced articles connected by a tape with the tape 25 passing through the notch, a trip adjacent the cutters and in the path of the articles, a spring connecting the trip to the pawl, said spring being stronger than the spring tending to cause the pawl to engage the ratchet, 30 but not strong enough to disengage the pawl during its working stroke.

In testimony whereof I have hereunto signed my name to this specification.

CARL G. KRONMILLER.
